UNITED STATES PATENT OFFICE

154,775

DESIGN FOR A PROJECTOR

Frederick W. Hertzler, Detroit, Mich., assignor to
Argus, Incorporated, Ann Arbor, Mich., a corporation of Michigan

Application March 28, 1949, Serial No. 1,678

Term of patent 14 years

(Cl. D61—1)

To all whom it may concern:

Be it known, that I, Frederick W. Hertzler, a citizen of the United States, residing at Detroit, in the county of Wayne and State of Michigan, have invented a new, original, and ornamental Design for a Projector, of which the following is a specification, reference being had to the accompanying drawing, forming a part thereof.

Figure 1 is a perspective view of a projector, showing my new design;

Figure 2 is a side elevational view of the projector of Figure 1;

Figure 3 is a top plan view of the projector of Figures 1 and 2;

Figure 4 is a rear elevational view of the projector of Figures 1 through 3;

Figure 5 is a front elevational view of the projector of Figures 1 through 4.

I claim:

The ornamental design for a projector, substantially as shown:

FREDERICK W. HERTZLER.
